(57) **CLAIM**

The ornamental design for a container with wide pour spout, as shown and described.

DESCRIPTION

FIG. 1 is a top view of a container with wide pour spout showing our new design;

FIG. 2 is a bottom view thereof;

FIG. 3 is a side view thereof;

FIG. 4 is a front view thereof;

FIG. 5 is a rear view thereof;

FIG. 6 is a forward upper perspective view thereof;

FIG. 7 is a forward lower perspective view thereof;

FIG. 8 a rear upper perspective view thereof;

FIG. 9 is a rear lower perspective view thereof;

FIG. 10 is an upper perspective view thereof in a usage condition;

FIG. 11 is an upper perspective view thereof in another usage condition; and,

FIG. 12 is an upper perspective view thereof in yet another usage condition.

The broken line portion of the figure drawings is included to show unclaimed subject matter only and forms no part of the claimed design.

1 Claim, 11 Drawing Sheets
